BELT BUCKLE

Arthur A. Oshlag, New Rochelle, N. Y.

Application March 8, 1952, Serial No. 18,826

Term of patent 7 years

(Cl. D17—1)

To all whom it may concern:

Be it known that I, Arthur A. Oshlag, a citizen of the United States, residing in New Rochelle, county of Westchester, State of New York, have invented a new, original, and ornamental Design for a Belt Buckle, of which the following is a specification, reference being had to the accompanying drawing, forming a part thereof, in which:

Fig. 1 is an elevational view of my new design for a belt buckle;

Fig. 2 is a side elevational view thereof, and
Fig. 3 is a front elevational view thereof.

I claim:

The ornamental design for a belt buckle, as shown.

ARTHUR A. OSHLAG.
